UNITED STATES PATENT OFFICE.

THEODOR SCHULZE, OF GUBEN, PRUSSIA, ASSIGNOR OF ONE-HALF TO
SYLVESTER GÖRNICKI, OF BERLIN, GERMANY.

WIND-WHEEL.

SPECIFICATION forming part of Letters Patent No. 355,034, dated December 28, 1886.

Application filed July 16, 1886. Serial No. 208,181. (No model.) Patented in Belgium July 17, 1886, No. 73,519; in England July 17, 1886, No. 8,068; in France July 17, 1886, No. 176,821, and in Spain July 17, 1886, No. 9,574.

To all whom it may concern:

Be it known that I, THEODOR SCHULZE, a subject of the King of Prussia, Empire of Germany, residing at the city of Guben, in the Kingdom of Prussia, Empire of Germany, have invented certain new and useful Improvements in Horizontal Wind and Water Motors, (patented in Belgium, No. 73,519, dated July 17, 1886; in England, No. 8,068, dated July 17, 1886; France, No. 176,821, dated July 17, 1886, and Spain, No. 9,574, dated July 17, 1886,) of which the following is a specification.

The object of my invention is to provide a new and improved wind or water motor of simple construction in which a very great surface on which the wind or water can act is obtained.

The invention consists in the combination, with a wheel, of wings pivoted on the same, and two concentric rings, one larger and the other smaller, provided with adjustable lugs against which the wings can rest, which lugs can be adjusted by a series of chains, all as will be fully described and set forth hereinafter, and pointed out in the claims.

In the accompanying drawings, Figure 1 is a plan view of my improved wind and water motor. Fig. 2 is a cross-sectional view of the same. Fig. 3 is an end elevation of the wind-motor, a portion being in section. Figs. 4 and 5 are detail side views of the adjustable lugs. Fig. 6 is an enlarged detail sectional view of the shaft, showing the rollers for the chains or wires for adjusting the lugs in position.

Similar letters of reference indicate corresponding parts.

In the drawings, *a* represents a series of wings, which are each provided with a shaft, *b*, journaled at the top and bottom in a ring, *d*, in such a manner that the shafts of the wings can turn freely on their longitudinal axes. The ring *d* is connected by spokes *e* with a hub on a vertical shaft, *A*, and on said spokes the rings *ff'*, the former smaller and the latter larger than the ring *d*, are secured concentric with said ring *d*. On the rings *ff'* the lugs *gg'* are pivoted, the upper ends of the lugs which project beyond the plane of the rings *f'*

being beveled in the opposite direction. The lugs *g* are provided with downwardly-projecting arms *M*, the arms *M* and the lugs *g'* being connected by rods *k*, pivoted to the lugs *g'* above the pivots of said lugs. Springs *i*, secured on the ring *f*, act on the downwardly-projecting arms *M* of the lugs *g*. The lugs *g'g'* are arranged on radial lines about midway between the shafts *b*, so that the lines connecting each shaft with its corresponding lug, *g'g'*, form about a right angle. Chains or wires *h*, that are secured to the lower ends of the several arms *M* of the lugs *g*, are passed over pulleys *k'*, fixed on a ring of the main shaft, and are provided on their lower ends with eyes which can be fastened to pins *k''*, projecting from a collar on the main shaft *A*. A wheel, *m*, having teeth on its inner edge and an arm, *m'*, is mounted loosely on the shaft *A* and adapted to engage with the teeth of a pinion, *n*, in which arm a roller, *m''*, is pivoted, the arm *m'* being of such length that the roller *m''* can act on those wings projecting over the ring or wheel *f*. The teeth of a pinion, *n*, engage with the teeth of a cog-wheel, *m'*, said pinion being mounted on the upper end of the shaft *n'*, journaled in an arm on the hub to which the wings are fastened, and in an arm, *O*, fixed on the shaft *A*. On the lower end of the shaft *n'* the bevel cog-wheel *n''* is mounted and engages with the bevel cog-wheel *n'''*, having a crank-handle, *n*, by means of which the bevel cog-wheels *n'' n'''* and the shaft *n'* and the pinion *n* on the same can be turned.

The operation is as follows: Under the action of the springs *i* the lugs *g'g'* are all in such position that their beveled ends project above the planes of the rings *ff'*, and the wings *a* in revolving can strike and rest against one of the said lugs. If the wind blows in the direction of the arrow *a'*, Fig. 1, it swings some of the wings *a* against the lugs *g'* on the outer ring, *f'*, and others against the lugs *g* on the inner ring, *f*, and others are in the line of the wind, as shown in dotted lines in Fig. 1. The wings change their position as the wheel revolves, and at all times the greater number of wings rests against the lugs, and the force of the said wings acting on the said lugs turns

the wheel. In case it is desired to throw any of the wings out of operation, the corresponding chain or wire, k^3 , is pulled downward, whereby the lugs operated by said chain are swung 5 down, so that the wings cannot rest against the lugs, but can rotate freely. Those wings at which the lugs $g\ g'$ are swung down do not assist in propelling the wheel, but are always in the direction of the wind. The lugs $g\ g'$ are 10 held lowered by fastening the rings on the lower ends of the corresponding chains on the pins k^2 . When it is desired to bring the said wings into action again, the chains are released, when the springs i swing the lugs $g\ g'$ 15 up. It is necessary, however, that the wings are brought into proper position, so that they can rest against the lugs. To accomplish this the shaft n' is turned by the crank-handle n^4 , whereby the arm m' is moved in the direction 20 of the arrow y . The roller m^2 on the end of the arm m' strikes those ends of the wings resting over the inner edge of the ring f , presses them against the beveled ends of the lugs g , projecting above the ring f , whereby the said lugs 25 are swung down until the wings have passed, then snap up and the wings are then in position to rest against the lugs. As the arm O is fixed on the shaft A , the pinion n , the wheel m , and the arm m' turn with the wind-wheel.

30 In case the motor is to be used as a water-motor, the adjusting-chains are arranged above the wheel instead of below.

Having thus described my invention, I claim as new and desire to secure by Letters Patent—

1. In a horizontal wind-motor, the combination, with two rings, of a series of wings pivoted on the same to swing on their vertical axes, lugs against which the wings rest, and a wheel having an arm for shifting the wings into position, substantially as shown and described. 35

2. In a horizontal wind-motor, the combination, with two rings, of a series of wings pivoted on the same to swing on their vertical axes, a pair of lugs for each wing against which the said wings can rest, mechanism for adjusting the position of the lugs, a cog-wheel, m , a pinion, n , engaging with the same, an arm, m' , on the wheel m , and mechanism for revolving said wheel m , substantially as shown and described. 45

3. In a horizontal wind-motor, the combination, with rings, of wings pivoted on said rings, pivoted lugs against which the wings can rest, the cog-wheel m , having the arm m' , 55 the roller m^2 on said arm, the pinion n , the shaft n' , the bevel cog-wheels $n^2\ n^3$, and chains for adjusting the positions of the lugs, substantially as shown and described.

In testimony whereof I have signed my name 60 to this specification in the presence of two subscribing witnesses.

THEODOR SCHULZE.
